(57) **CLAIM**

The ornamental design for a display screen or portion thereof with animated graphical user interface, as shown and described.

DESCRIPTION

FIG. 1 is a front view of a first image of a display screen or portion thereof with animated graphical user interface;

FIG. 2 is a second image thereof;

FIG. 3 is a third image thereof; and,

FIG. 4 is a fourth image thereof.

The broken lines showing the display screen or portion thereof form no part of the claimed design.

The appearance of the animated images transitions sequentially between the images shown in FIGS. 1-4. The process or period in which one image transitions to another forms no part of the claimed design.

1 Claim, 4 Drawing Sheets
